UNITED STATES PATENT OFFICE.

FELIX LOUIS DECARIE, OF MONTREAL, QUEBEC, CANADA.

BOILER.

Application filed October 25, 1919. Serial No. 333,194.

This invention relates to steam boilers, and particularly to boilers of the tube type, wherein water is circulated through heated tubes.

5 The main object of this invention is the provision of means to increase circulation through the boiler tubes, thereby preventing the water from backing up at the ends of the tubes.

10 A further object of the invention is to construct a boiler head wherein the tubes are held in spaced relation by suitable plates which form partitions, for partitioning the heads into compartments.

15 Referring to the drawing:—

Figure 1 illustrates a sectional view through a tube boiler.

Figure 2 is a modified form of header.

Figure 3 is a vertical sectional view taken 20 on line 3—3 of Figure 2.

Figure 4 is a side elevation view of a furnace with a boiler constructed in accordance with my invention.

25 Figure 5 illustrates a sectional view of a modified form of header.

Figure 6 illustrates a horizontal sectional view thereof.

Referring to the drawings in detail, reference character 5 indicates a header, which 30 has communication at its upper end with the boiler 6 through nipple 7, and with the opposite end thereof through pipe 8 which connects with the boiler 6 at the rear thereof.

The rear wall 9 of the header 5 is provided with a plurality of openings 10 in which are supported at one of their ends the horizontally disposed water tubes 11, and 35 which as shown have communication with said header 5. The opposite ends of the water tubes being closed as by caps 14.

The front wall 12 of the header 5 is also provided with threaded openings, indicated at 13, which openings are disposed directly in alignment with the openings 10 of the rear wall 9, for purposes to be hereinafter 40 more fully described.

To facilitate the circulation and heating of the water within the water tubes 11, I have provided a horizontal partition 15 in each of the tubes, one end of the partitions being connected to the respective threaded plugs 16, which are positioned in the openings 10 of the header. These partitions 15 extend through the water tubes 11 and close-

ly engage the inner wall 17 thereof, the inner ends of said partitions terminating short of the ends of the water tubes in which the same are supported, to provide a space between the ends of the partitions and their tubes, thereby allowing free passage of fluid 55 through the compartments formed in the tubes by the partitions.

In the modified form of the invention, as shown by Figure 4 of the drawings, the water tubes 11' are arranged in groups, each 60 group having an independent header 12' to which the water tubes 11' are connected. These headers 12', as shown, have communication with the boiler proper 12", through vertical pipes 13", and said pipes having one 65 of their ends connected to the heads through the openings 14" formed in the upper walls of the heads 12".

As indicated by the drawings, each of the tubes 11' is provided with a central partition dividing the same into compartments 70 13" and 14", whereby circulation through the tubes 11' is maintained, at all times.

With reference to Figure 2, the same illustrates a modified form of a header, which 75 as shown has curved walls 20, an intake opening 21, at the bottom thereof and exhaust opening 22 at the top, the curved side walls of the header forming irregular passage ways for water circulating around the 80 ends of the water tubes 23, which as shown are disposed in staggered relation with each other. A drain opening 28 is provided at the base of the header to permit the water within the boiler and tubes to be drained 85 off and replenished.

Metallic partitions 24 and 30 divide the header into vertical compartments 25 and 26, which compartments communicate through the water tubes 23, the partitions 24 and 30 90 contacting with the ends of the tubes.

In Figure 1 of the drawings I have shown a gas burner 27 disposed directly under the water tubes 11. This burner, however, may of course be supplemented by the ordinary 100 fire box, as illustrated by Figure 4.

Having now described my invention, what I claim is:—

In a boiler construction, a body portion, a header at one end of the body portion, tubes 105 extending into the body portion and communicating with the header, said tubes being disposed in staggered relation with re-

spect to each other, removable partitioning members, alternate vertical and obliquely disposed partitioning walls in said header contacting with the ends of adjacent tubes and with opposite edges of the respective removable partitioning members to form two longitudinal passages through said header,

there being an inlet to one of said passages through one end of the header, and an outlet for the other passage at the opposite end ¹⁰ of said header.

In testimony that I claim the foregoing as my own, I have hereto affixed my signature.

FELIX LOUIS DECARIE.
